VAPOR GENERATOR

Leon H. Coykendall, Westfield, N. J., assignor to
The Babcock & Wilcox Company, New York,
N. Y., a corporation of New Jersey

Application November 5, 1949, Serial No. 125,756

2 Claims. (Cl. 122—1)

1

The present invention relates in general to the construction and operation of vapor generators and more particularly, to fuel-fired steam generators or boilers of the water tube type having provision for heating air required for the combustion of fuel in an associated furnace. In the practice of my invention, I contemplate, among various permissible embodiments, a form of water tube steam boiler having a large proportion of its heating surface in the form of upright steam generating tubes arranged laterally of the furnace combustion chamber and disposed in successive gas passes through which the hot gaseous products of combustion are directed in series along a substantially horizontal gas flow path. The complete boiler unit may also include a superheater disposed intermediate groups of boiler tubes in one or more of the passes and, for adequate efficiency at high ratings, may further include additional tubular heating surface in the form of a boiler feed water heater or economizer disposed in the path of the heating gases either before or after the gases are discharged from the boiler setting.

According to customary prior practice, the total quantity of gases generated in the boiler furnace is directed over all boiler, superheater and economizer surface and thereafter, at the resulting reduced temperature, is directed over air heater surface prior to final discharge to the stack. In conventional forms of air heaters, wherein heat is transferred from combustion gases to combustion air, the transfer of heat is effected through the medium of metallic heat transfer elements either in the form of spaced tubes or plates. Each such heat transfer element provides opposite surface areas which, in the recuperative type of air heater, are contacted by the respective fluids, gas and air, simultaneously, whereas, in the regenerative type of air heater, for corresponding elements or material, all major exterior surface areas thereof are contacted by the gas during one period of operation, and by the air during another period of operation. In either type of air heater, generally counterflow relation of air flow to gas flow is ordinarily maintained so as to provide the maximum rate of heat transfer from one fluid to the other.

In the operation of an air heater, of either of the above mentioned types, it is known that those portions of the heat transfer elements adjacent the cold air inlet are subject to fairly rapid corrosion unless the air heater is operated so as to maintain all portions of such elements adjacent the air inlet zone at temperatures high

enough to prevent the condensation of vapors flowing in contact therewith. The corrosive effect mentioned is generally the result of the condensation of water vapor carried by the heating gases flowing in contact with the metallic heat transfer surfaces, combined with the presence of a gaseous constituent such as sulphur dioxide resulting from combustion of the fuel by which the gases are generated. Condensation of the aqueous vapor also maintains the low temperature surfaces in a moist condition which is conducive to the collection of dust particles thereon and to a consequent decrease in heat transfer efficiency. When the gas flow passages are of relatively small area or width, and particle carrying gases are directed therethrough, such passages are liable to become plugged and the effectiveness of the heat transfer elements thus completely nullified.

The condensation is promoted when the metal of certain portions of the heat transfer elements is compelled to operate continuously at relatively low temperatures; for example, in an air heater of the recuperative type, those portions of the tubes or plates adjacent the cooler gas exit end, due to the continuous contact of cold inlet air with one surface, and to the continuous contact of cooled gases with the opposite surface. Similarly, in an air heater of the regenerative type, those portions of the heat transfer elements or material most susceptible to corrosion due to low temperature operation are the portions which, during alternate periods of operation are adjacent the gas outlet zone and thus swept throughout by cooled outgoing gases, and during the remaining alternate periods of operation are adjacent the air inlet zone and thus similarly swept by the cold entering air.

My invention is therefore concerned with an improved form of vapor generator or boiler whereby combustion gases of adequately high temperature are made available for use as the heating fluid in a heat exchanger located exteriorly of the boiler setting, the purpose being to maintain the metal of the heat transfer elements above the temperature at which condensation of vapor carried by the gases takes place. As will be understood from preceding remarks, the maintenance of the heat transfer metal at relatively high temperatures is of particular importance in heat exchangers of the type wherein, as in an air heater, the fluid to be heated is continuously admitted at relatively low ambient temperatures.

In accordance with my invention, I therefore propose a form of vapor generator in which provision is made for the withdrawal of heating

gases, under suitable regulation, from an intermediate point in the gas flow path throughout the boiler where such gases are at an appreciably higher temperature than the gases normally delivered to the air heater from the usual gas outlet. The gases thus withdrawn are then directed to the gas inlet of the air heater for mingling with the main heating gas supply so as to result in an increase in the initial temperature of the total entering gas stream. Such an arrangement is effective in maintaining temperatures of all portions of the metallic heat transfer elements above the temperature of vapor condensation and is therefore advantageous when the boiler is being operated at low capacities, particularly under conditions of low capacity operation over an extended period when the heating gases discharged from the usual boiler outlet are continuously at temperatures too low to prevent condensation of vapor on air heater element portions adjacent the cold air inlet. A specific illustration of the necessity of low capacity boiler operation over extended periods is found in hydroelectric plants where auxiliary steam turbine-driven electric generators are customarily maintained in operation as a so-called "spinning reserve" so as to be available for operation at greatly increased load whenever the demand occurs.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a front elevation view, partly broken away, of a vapor generator or boiler representing a structural embodiment of my invention;

Fig. 2 is a sectional plan view, partly broken away, of the boiler illustrated in Fig. 1, taken along line 2—2; and

Fig. 3 is side elevational view, partly broken away, of the boiler illustrated in Figs. 1 and 2.

As illustrated herein, the selected embodiment of my invention comprises a vapor generator or boiler having a convection boiler tube section 42 disposed in laterally adjacent relation to the furnace combustion chamber 13, within a common setting of substantially rectangular horizontal cross section, the setting being defined in part by fluid cooled upright front and rear walls 14 and 15, and by fluid cooled upright boiler and furnace side walls 16 and 17. The combustion chamber is formed with a hopper bottom portion 18 having a lower ash discharge throat 19. Provision is made for discharging fuel into the combustion chamber through the front wall 14 by burners, not shown, grouped within the windbox 21 at locations indicated by the burner support plates 23.

The boiler section 12 occupies a boiler tube space 24 which lies adjacent the uppermost portion of combustion chamber 13 and which is partitioned therefrom by an upright fluid cooled wall 25 forming an upper continuation of a lower side wall boundary 26 of chamber 13, the partition wall 25 extending from front wall 14 to a point forwardly spaced from the rear wall 15 so as to define therewith a common gas-outlet and gas-inlet 27 through which heating gases flow

from chamber 13 into the boiler section space 24. Boiler section 12 comprises an upper steam and water drum 28 and a lower water drum 29, horizontally disposed and arranged in substantially vertical alignment. Horizontally spaced upright boiler tubes 31 extend between the drums 28 and 29 to which the upper and lower ends of tubes 31 are connected substantially throughout the length of boiler tube space 24 between the front and rear walls 14 and 15.

The boiler section space 24 is transversely divided by spaced upright baffles 32 and 34 so as to define a succession of serially connected gas passes 35, 36 and 37 through which the heating gases from chamber 13 are directed in a substantially horizontal path over successive boiler tube groups or banks 31a, 31b, 31c, disposed in the respective passes. A multiple loop superheater 41 having tubes of the formation indicated in Fig. 1, and having vapor inlet connections 42 with upper drum 28, is disposed within the first transverse gas pass 35, intermediate front and rear rows of tubes of the boiler tube group 31a.

The hot heating gases resulting from the combustion of fuel in chamber 13 thus enter the tube space 24 through the inlet passage 27 and flow in a generally horizontal direction throughout the successive gas passes 35, 36 and 37, wherein the gases are directed transversely of all boiler and superheater surface contained in the respective passes. A main heating gas outlet 43 is provided at the bottom of the final gas pass 37 through which heating gases are discharged from the boiler setting.

A gas outlet duct 45, having a gas flow connection with the boiler gas outlet 43, provides a flue through which the gases are directed downwardly over a boiler feed water heater or economizer 46 located therein, the economizer being formed with a bank of tubes 47 extending throughout the horizontal cross section of the flue and arranged in continuous coils or platens, as indicated in Fig. 1; the tubes 47 having opposite ends connected to inlet and outlet headers 48 and 49, respectively, the inlet header 48 having a connection to a source of feed water supply; and the outlet header 49 having a connection to the upper boiler drum 28, neither of which connections is illustrated. Gases leaving the economizer tube bank 47 are discharged from duct 45 through a side outlet 51 under regulation of a multi-leaf damper 52, having an exterior operating mechanism 53.

Upon discharge from the economizer duct 45, the heating gases pass directly to an air heater 54 which, in the form herein indicated is of the regenerative, indirect heat transfer type and which, for the purposes of this disclosure may be of the same general construction as the regenerative heating device illustrated in U. S. Patent No. 1,558,445, issued October 20, 1925. Accordingly, the air heater 54, as shown, comprises a stationary casing 56 having an intermediate cylindrical section 57 which contains a rotor, to be later described, and opposite end sections 58 and 59 of which each is horizontally divided by a diaphragm 61 so as to form upper and lower compartments 58a, 58b and 59a, 59b at the respective ends. The rotor, not shown, which provides the metallic heat transfer elements, is suitably mounted for rotation about a central horizontal axis coinciding with the plane of the diaphragms 61 at opposite ends. The heat transfer elements which constitute the regenerative material may be provided in the form of closely spaced metallic plates

which extend axially of the rotor so as to define a multiplicity of axially extending channels or passages which, during rotation of the rotor, provide fluid flow paths connecting opposite end compartments 58a and 59a, above partitions 61, and other fluid flow paths connecting opposite end compartments 58b and 59b, below the partitions.

Gases discharging from the economizer duct 45 are thus directed into the upper, gas inlet compartment 58a of air heater 54, and are then conducted through the connecting rotor channels into the upper gas outlet compartment 59a from which the gases are discharged through the gas outlet duct 62, under the influence of suitable induced draft fan means, not shown. Air is supplied to the air heater, suitably by means of a forced draft fan 63, and is directed into the lower, air inlet compartment 59b from which it is conducted through the connecting rotor channels into the lower, air outlet compartment 58b from which the air passes into suitable conduit means comprising an air delivery duct 65 by which the heated air is supplied to the burner windbox 21.

During operation of air heater 54, gas flow is confined to passages at the upper side of diaphragms 61, and is countercurrent to air flow which is confined to passages at the lower side of the diaphragms. Continuous rotation of the rotor in one direction results in each axial rotor channel serving as a gas conducting channel during one-half of each revolution and the same channel serving as an air conducting channel during the remaining half revolution. Thus, the radially extending metal plates which provide the walls of the channels are swept by heating gases during the upper half of each revolution and by air to be heated during the remaining lower half revolution. These metal plates which constitute the regenerative material thus present end portions toward the gas outlet-air inlet end of the air heater and consequently are alternately swept by cooled gases and by the cold entering air whereby the mean temperature of the metal of such end portions remains relatively low throughout operation. During extended periods of low capacity operation of the associated boiler, these low temperature portions of the metallic regenerative material are therefore subject to corrosion as the result of condensation of vapor thereon. It will be understood, of course, that if such plates were made of a non-corrosive metal, the cost of the air heater might be prohibitive commercially. Furthermore, the substitution of a non-corrosive metal would in itself not prevent condensation and the resulting collection of ash particles on the heat transfer surfaces.

As a means of maintaining higher metal temperatures throughout air heater 54, particularly at the cold air inlet end, the boiler is provided with a secondary gas outlet 68 formed in the boiler side wall 16 adjacent the lower end of the second transverse gas pass 36 and thus at a location downstream of the superheater 41 with respect to heating gas flow thereover. A gas bypass duct 69, exteriorly of the setting, extends from the gas outlet 68 to the air heater 54 where connection is made through opening 71 with the gas inlet compartment 58a. Gas flow into and through the bypass duct is regulated by means of a damper means 72 disposed across the gas outlet 68. As a result of providing the gas bypass connection to the air heater, hotter gases are

directed into the gas inlet compartment 58a than are delivered thereto from the economizer duct 45. The two gas streams become mingled in the gas inlet compartment 58a and thereby provide, for passage through the rotor channels, a body of heating gases of considerably higher temperature than the gases available from a single gas outlet in the usual boiler construction. If gases of the maximum available temperature are to be directed through air heater 54, the damper 52 may be closed entirely, and the bypass damper 71 left open, so as to cause substantially the total quantity of gases to pass through the bypass duct 69, while only a negligible proportion is permitted to pass over the economizer. The arrangement herein disclosed is of particular utility, during extended periods of low capacity boiler operation, due to the fact that under such conditions, the economizer may be operated at correspondingly reduced capacity so that no disadvantage results from the reduction of gas flow over the economizer.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A vapor generator comprising horizontally disposed upper and lower drums, vapor generating tubes extending upright between said drums and connected thereto along the length thereof, an upright partition forming the inner side wall boundary of a combustion chamber laterally adjoining the space containing said tubes and separated therefrom except at one end by said partition so as to provide a heating gas entrance to said space, upright baffle means extending transversely of said partition and arranged to divide said space into a plurality of serially connected gas passes throughout which said tubes are distributed, means for burning fuel in said chamber and effecting a flow of heating gases through said entrance and successively through said passes in contact with said tubes, said space having a main gas outlet discharging a main gas stream from the pass farthest from said entrance and having a secondary gas outlet discharging a secondary gas stream from a preceding gas pass, an air heater disposed externally of said space and having a heating gas inlet and a heated air outlet, dampered conduit means separately connecting said main and secondary gas outlets to said air heater gas inlet, an economizer for heating vaporizable liquid to be fed to one of said drums, said economizer being positioned in said conduit means conducting said main gas stream to said air heater gas inlet, and conduit means conducting heated air from said air heater air outlet to said fuel burning means.

2. A vapor generator comprising horizontally disposed upper and lower drums, vapor generating tubes extending upright between said drums and connected thereto along the length thereof, an upright partition forming the inner side wall boundary of a combustion chamber laterally adjoining the space containing said tubes and separated therefrom except at one end by said partition so as to provide a heating gas entrance to said space, said combustion chamber extending

downwardly past said lower drum so as to form an exterior recess between an outer side wall boundary of said chamber and the lower boundary of said space, upright baffle means extending transversely of said partition and arranged to divide said space into a plurality of serially connected gas passes throughout which said tubes are distributed, means for burning fuel in said chamber and effecting a flow of heating gases through said entrance and successively through 10 said passes in contact with said tubes, said space having a main gas outlet discharging a main gas stream from the lower end portion of the pass farthest from said entrance and having a secondary gas outlet discharging a secondary gas stream from the lower end portion of a preceding one 15 of said passes, an air heater disposed within said recess and having a heating gas inlet and a heated air outlet, dampered conduit means separately connecting said main and secondary gas outlets to said air heater gas inlet, an economizer for heating vaporizable liquid to be fed to one of 20

said drums, said economizer being positioned in said conduit means conducting said main gas stream to said air heater gas inlet, and conduit means conducting heated air from said air heater air outlet to said fuel burning means.

LEON H. COYKENDALL.
